Filed May 5, 1971, Ser. No. 140,641

Term of patent 14 years

Int. Cl. D23—04

U.S. Cl. D23—139

FIG. 1

FIG. 2

FIG. 3

FIG. 1 is a perspective view of the combined refrigeration unit and air duct for dwellings showing my new design.

FIG. 2 is a side elevational view thereof;

FIG. 3 is a rear elevational view thereof on a slightly reduced scale.

The roof is shown in broken lines for illustrative purposes only.

The characteristic features of my design reside in the sloping lower edge of the sides and the downwardly sloping top plane which forms an apex with the sloping lower edge.

I claim:

The ornamental design for a combined refrigeration unit and air duct for dwellings, as shown and described.
